UNITED STATES PATENT OFFICE.

JAMES TIMMS, OF COLUMBUS, OHIO.

DESIGN FOR A KNUCKLE FOR CAR-COUPINGS.

SPECIFICATION forming part of Design No. 35,148, dated October 1, 1901.

Application filed June 26, 1901. Serial No. 66,167. Term of patent 14 years.

To all whom it may concern:

Be it known that I, JAMES TIMMS, of Columbus, in the county of Franklin and State of Ohio, have invented and produced a new and original Design for Knuckles for Car-Couplings; and I do hereby declare the following to be a full, clear, and exact description of the invention, such as will enable others skilled in the art to which it appertains to make and use the same.

In the accompanying drawings, Figure 1 is a top plan view of the knuckle. Fig. 2 is a front side elevation. Fig. 3 is a rear side elevation. Fig. 4 is a front end view. Fig. 5 is a rear end view.

The jaw 1 of the knuckle is made with a flat front face and is slotted at 2 and provided with vertical holes 3. The body 4 of the knuckle is curved and has a vertical hole 5. The inner end of the body portion 4 is contracted and somewhat tapering, and at the smaller end of this contracted tapering portion the tail 6

is located and projects rearwardly. The tail is disposed diagonally with relation to the body of the knuckle, tapers toward its free end, and has a curved edge 7, an inclined face 8, and a lower face 9, which has a somewhat greater degree of inclination. The top of the tail at the inner end of the upper inclined face 8 has a depression 9^a, and at the inner end of the curved edge 7 of the tail a lip 10 is located.

Having fully described my design, what I claim as new, and desire to secure by Letters Patent, is—

The design for a knuckle for a car-coupling, herein shown and described.

In testimony whereof I have signed this specification in the presence of two subscribing witnesses.

JAMES TIMMS.
